(57) **CLAIM**

The ornamental design for a combination whisk broom with squeegee and dustpan, as shown and described.

DESCRIPTION

FIG. 1 is a perspective view of a combination whisk broom with squeegee and dustpan according to the present invention;

FIG. 2 is a front view of the combination whisk broom with squeegee and dustpan of FIG. 1;

FIG. 3 is a rear view of the combination whisk broom with squeegee and dustpan of FIG. 1;

FIG. 4 is a first side view of the combination whisk broom with squeegee and dustpan of FIG. 1;

FIG. 5 is a second, opposite side view of the combination whisk broom with squeegee and dustpan of FIG. 1;

FIG. 6 is a bottom view of the combination whisk broom with squeegee and dustpan of FIG. 1;

FIG. 7 is a top view of the combination whisk broom with squeegee and dustpan of FIG. 1; and,

FIG. 8 is a perspective view of the combination whisk broom with squeegee and dustpan of FIG. 1 with the dustpan separated from the combination broom with squeegee.

1 Claim, 8 Drawing Sheets
